[57] **CLAIM**

The ornamental design for a kiddie dental holder, as shown and described.

DESCRIPTION

FIG. 1 is a front elevational view of a kiddie dental holder showing my new design;

FIG. 2 is a right side elevational view thereof;

FIG. 3 is a rear elevational view thereof;

FIG. 4 is a bottom plan view thereof;

FIG. 5 is a top plan view thereof; and,

FIG. 6 is a left side elevational view thereof.

The broken lines shown in FIGS. 1, 2, 3, 5 and 6 are for illustrative purposes only and form no part of the claimed design.
